(57) **CLAIM**

The ornamental design for a smart watch, as shown and described.

DESCRIPTION

FIG. 1 is a front perspective view of a smart watch, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of a portion of the area 9 in FIG. 1;

FIG. 10 is an enlarged detail view of a portion of the smart watch shown in area 10 in FIG. 7;

FIG. 11 is an enlarged detail view of a portion of the smart watch shown in area 11 in FIG. 7; and,

FIG. 12 is an enlarged detail view of a portion of the smart watch shown in area 12 in FIG. 7.

The broken lines in the drawings illustrate the portions of the smart watch, that form no part of the claimed design.

The dash-dot-dash broken lines encircling the enlarged views are for annotative purposes only and form no part of the claim thereof.

1 Claim, 12 Drawing Sheets
